UNITED STATES PATENT OFFICE.

ALBERT ERICKSON, OF CHICAGO, ILLINOIS, ASSIGNOR TO SPLITDORF ELECTRICAL COMPANY, OF NEWARK, NEW JERSEY, A CORPORATION OF NEW JERSEY.

IGNITION DEVICE FOR INTERNAL-COMBUSTION ENGINES.

Application filed July 21, 1919. Serial No. 312,228.

To all whom it may concern:

Be it known that I, ALBERT ERICKSON, a citizen of the United States, residing at Chicago, in the county of Cook, State of Illinois, have invented certain new and useful Improvements in Ignition Devices for Internal-Combustion Engines, of which the following is a description, reference being had to the accompanying drawing, and to the figures of reference marked thereon.

The invention relates to new and useful improvements in ignition devices, and more particularly to an ignition device having a fixed and a movable electrode to which current is supplied by a magneto generator.

An object of the invention is to provide an ignition device of the above character, wherein the trip lever for placing the actuating spring under compression and releasing the same is mounted directly on the armature shaft of the magneto, and wherein the magneto is removably mounted on a bracket attached to the engine cylinder.

A further object of the invention is to provide an ignition device of the above character, wherein the main actuating spring for the trip lever encircles and is supported by a bearing sleeve carried by the frame of the magneto and in which the armature shaft oscillates.

A further object of the invention is to provide an ignition device wherein the fixed and the movable electrodes are carried by one bracket and the magneto, together with the trip lever and the main actuating spring are carried by another bracket and the two brackets are secured to the engine cylinder by common means, which when removed, releases the two brackets from all connection, so that either bracket may be renewed or replaced without requiring changes or alterations in any way in the other bracket.

A still further object of the invention is to provide an ignition device of the above character, wherein the bracket carrying the magneto generator is provided with a terminal having yielding means forming an electrical connection with the stationary electrode.

These and other objects will in part be obvious and will in part be hereinafter more fully described.

In the drawings which show by way of illustration one embodiment of the invention—

Figure 1 is a view showing more or less diagrammatically, the engine cylinder and the bracket connected thereto which supports the fixed and movable electrodes;

Figure 2 is an end view of the other bracket with the magneto generator mounted thereon;

Figure 3 is a vertical section through the ignition device, showing the parts attached to an engine cylinder;

Figure 4 is a horizontal sectional view of the same on the line 4—4;

Figure 5 is a detail showing one of the locking pins for holding the bearing for the armature shaft in place.

The invention consists broadly in an ignition device for internal combustion engines, which includes a generator having an armature which is adapted to be oscillated in a magnetic field for producing a current for furnishing the ignition spark. Mounted in the frame of the magneto generator is a bearing in which one end of the armature shaft is journaled and said shaft extends beyond the bearing and a trip lever is mounted rigidly on the end of said shaft. The bearing is extended in sleeve form and the main spring is wound about said bearing, one end of the spring being attached to the bearing and the other end to the trip lever, so that when the trip lever is moved by the usual push rod, the main spring will be put under tension and upon the release of the trip lever said spring will rotate the armature shaft for generating the current for ignition purposes.

This magneto generator is mounted on a bracket which is separate and independent from the bracket which carries the fixed and movable electrodes, although the two brackets are secured to the engine cylinder by one and the same means. Positioning studs are provided to assist in the positioning of one bracket relative to the other when on the engine. The fixed and the movable electrodes are mounted in the bracket attached directly to the engine cylinder and the movable electrode is held seated by means of a small coil spring encircling the same which also serves to close the electrodes. This spring

is normally of greater tension than the tension of the main spring, so that when the parts are in normal position the electrodes are closed. When the trip lever is released 5 the armature is oscillated by the main spring and said trip lever will be caused to strike a cam arm fixed to the movable electrode and separate said electrodes.

Referring more in detail to the drawings, 10 my improved ignition device consists of a fixed electrode 1 and a movable electrode 2. These electrodes are provided with the usual contact points. The fixed and the movable electrodes are mounted in a bracket 3 having a tapered extension 4 adapted to fit a tapered opening in the wall of the engine cylinder, which is indicated at C in the drawings. The movable electrode 2 is carried by a shaft 5 which is journaled in a 15 bearing and on the outer end of said shaft is an arm 6 which is formed with a cam face 7^a, see Figure 1. Encircling the shaft between the arm and the bracket 3 is a coil spring 7, one end of which is attached to a 20 pin 8 mounted in the bracket, and the other end of which is attached to the arm 6. This coil spring serves the double function of holding the movable electrode seated in the bracket 3 and also of rotating the shaft 5, 25 so as to cause the ignition points of the electrodes to be closed. The fixed electrode 1 is carried by a rod 9, which extends through the bracket and has a nut 10 threaded thereon. Rigidly carried by the engine cylinder 30 35 is a stud 11 which extends through the bracket 3 and serves as a means for holding the bracket rigidly on the engine cylinder.

Associated with the fixed and movable electrodes is a magneto generator, indicated 40 at G in the drawings. Said generator is provided with a base or magneto frame 12. Mounted on this frame is a magnet 13 forming a magnetic field. An armature 13^a is mounted to oscillate in said magnetic field. 45 Said armature includes a shaft 14. This shaft at its outer end is journaled in a bearing 15 formed as a part of the frame and at its inner end in a removable bearing 16. This removable bearing 16 is provided with 50 an extended sleeve 17. Said bearing 16 fits within the frame and is held in position in the frame by pins, one of which is indicated at 18 in Figure 5 of the drawings. Said pin 18 is adapted to register with a recess 55 19 in the side face of the bearing 16 and the two pins not only hold the bearing from endwise movement but also hold the bearing from circular movement in the frame of the magneto. Mounted on the extreme inner end 60 65 of the shaft 14 is a trip lever 20. Said trip lever is formed with a shoulder at 21 which is adapted to be engaged by the ordinary push rod which in turn is actuated by the engine. Said trip lever is also provided 65 with a projecting finger 22 which serves

to positively disconnect the trip lever from the shoulder 21. Said trip lever is also provided with a handle 23, by means of which the trip lever may be actuated by hand, for producing a spark, when desired. Said trip lever is further provided with a cam shoulder 24 which is adapted to engage the cam shoulder 7^a carried by the arm 6 attached to the outer end of the shaft supporting the movable electrode. The main spring 25 encircles the sleeve 17 and at one end is connected to a pin 26 carried by the bearing 16, and at its other end is connected to a pin 27 mounted in the trip lever. This spring serves as the main spring for actuating the armature and also for separating the electrodes. The coil spring 7 is of greater tension than the main spring 25, when the parts are in normal position—that is, at rest, and, therefore, the movable electrode will be held in engagement with the fixed electrode. 70 75 80 85

In operation the push rod engaging the shoulder 21 moves the trip lever so as to put the main spring under compression and at a predetermined point said trip lever is released, then the spring actuates the armature and the cam shoulder 24 carried thereby will strike the cam shoulder 7^a carried by the arm fixed to the movable electrode and move said movable electrode so as to separate the contacts and produce a spark. This occurs, of course, at the time when the armature is at its maximum current generating position. 90 95

The magneto G is removably mounted on a bracket 28. Said bracket 28 has an outwardly projecting shelf and the generator is bolted thereto by suitable bolts 29. Said bracket, as clearly shown in Figure 2 of the drawings, is provided with a vertical section 30, having a face portion 31, which is milled to fit the front face of the bracket 3 and said vertical section 30 has an opening 32 which fits over the stud 11 threaded into the engine cylinder, and a nut 33 on the end of the stud clamps the bracket section 30 against the face of the bracket 3 and the bracket 3 against the face of the engine cylinder. The bracket 3 is formed with similar positioning studs 34, which are adapted to engage suitable openings 35 formed in the face portion 31 of the bracket section 30. These positioning studs serve to position one bracket relative to the other and assist in preventing the brackets from turning one relative to the other when on the engine. 105 110 115 120

Mounted in the bracket section 30 is a short bolt 36, which is connected to the terminal wire 37 of the magneto generator. At the inner end the bolt 36 is formed with a recessed head 38 in which is placed a spring 39, and said spring bears against a plate 40 which is forced outwardly by said spring. The recessed head overlies the plate and limits the outward movement of the plate. The fixed electrode rod 9 is of such 125 130

length as to bear against this plate 40, compressing the spring underneath the same and thus insuring a suitable electrical connection between the terminal 37 and the 5 fixed electrode. This fixed electrode is suitably insulated and the movable electrode is grounded, thus forming a return circuit to the grounded terminal of the magneto.

By making the supporting means for the 10 magneto generator and the electrodes independent—that is, by using two brackets, it will readily be seen that the electrode bracket may be renewed without renewing the bracket on which the magneto generator is mounted. Furthermore, if the magneto generator bracket becomes broken it 15 may be readily renewed without renewing the bracket for the electrodes.

It will be noted that my improved ignition 20 device is of comparatively few parts, which are compactly arranged, thus producing a very simple device, and said device is free from all adjustments, so that it is impossible for the parts to get out of timing or synchronization.

It is obvious that minor changes in the 25 details of construction and the arrangement of parts may be made without departing from the spirit of the invention, as set forth in the appended claims.

Having thus described my invention, what I claim as new and desire to secure by Letters Patent, is:

1. In an ignition device, a fixed and a 35 movable electrode, a magneto generator having a shaft carrying a current generating member, bearings in which said shaft is mounted, one of said bearings including a projecting sleeve, a coil spring encircling 40 said projecting sleeve, an arm on said shaft to which one end of said coil spring is connected, means for placing said spring under compression and means on the arm itself for releasing the same for actuating the 45 shaft, and means actuated by said spring for separating said electrodes at the time of maximum current generation in said magneto.

2. In an ignition device, a fixed and a 50 movable electrode, a magneto generator having a shaft carrying a current generating member, a removable bearing for one end of said shaft, a sleeve carried by said removable bearing, a coil spring encircling 55 said shaft and connected at one end to said bearing and at its other end to the shaft, which spring is adapted to be put under compression and released for actuating the current generating member, and means for 60 removably securing said bearing in the frame of the magneto generator.

3. In an ignition device, a fixed and a 65 movable electrode, a magneto generator having a shaft carrying a current generating member, a removable bearing for one

end of said shaft, a sleeve carried by said removable bearing, a coil spring encircling said shaft and connected at one end to said bearing and at its other end to the shaft, which spring is adapted to be put under 70 compression and released for actuating the current generating member, and means for removably securing said bearing in the frame of the magneto generator, said means including pins engaging recesses in the bearing for holding the bearing from endwise movement and from circular movement. 75

4. In an ignition device, a fixed and a movable electrode, a magneto generator having a shaft carrying a current generating member, a removable bearing for one end of said shaft, a sleeve carried by said removable bearing, a coil spring encircling 80 said shaft and connected at one end to said bearing and at its other end to the shaft, which spring is adapted to be put under compression and released for actuating the current generating member, means for removably securing said bearing in the frame of the magneto generator, a trip lever 85

on the end of said shaft, a cam projection carried by said trip lever, a shaft carrying the movable electrode, a spring for turning said shaft carrying the movable electrode for normally holding the electrodes in contact, said shaft having an arm adapted to be engaged by the trip lever when moved by the main spring, so that said electrodes will be separated in timing with the maximum current generation. 90

5. In an ignition device, a fixed and a movable electrode, a bracket in which said electrodes are mounted, a magneto generator, a bracket on which said magneto generator is mounted, means for securing the magneto generator bracket to the bracket carrying the movable electrode and said bracket carrying the movable electrode to the engine cylinder, one of said brackets having positioning pins adapted to engage recesses 95 formed in the other bracket. 100

6. In an ignition device, the combination of a bracket, a fixed and a movable electrode mounted therein, a second bracket, a magneto generator mounted on said second bracket, a main spring surrounding the shaft of the magneto generator and a trip lever for said magneto generator mounted on said second bracket, means whereby said trip lever operates to separate the electrodes, and common means for securing the two brackets together and against the engine cylinder. 115

7. In an ignition device, the combination of a bracket, a fixed and a movable electrode mounted therein, a second bracket, a magneto generator mounted on said second bracket, a main spring surrounding the shaft of the magneto generator and a trip lever for said magneto generator mounted 120

on said second bracket, means whereby said trip lever operates to separate the electrodes, common means for securing the two brackets together and against the engine cylinder, and positioning pins carried by one of said brackets and adapted to engage recesses in the other bracket.

8. In an ignition device, the combination of a bracket, a fixed and a movable electrode mounted therein, a second bracket, a magneto generator mounted on said second bracket, a main spring surrounding the shaft of the magneto generator and a trip lever for said magneto generator mounted on said second bracket, means whereby said trip lever operates to separate the electrodes, and a yielding terminal connection carried by the bracket supporting the magneto and

adapted to engage the end of the rod supporting the fixed electrode. 20

9. An ignition device, a bracket, a movable and a fixed electrode mounted in the bracket, a spring carried by the bracket, a spring carried by the bracket normally holding the electrodes closed, a second bracket, a magneto generator mounted thereon, a spring surrounding the shaft of the magneto generator and adapted to be compressed and released for actuating the armature of the magneto generator and having means for separating the electrodes, a yielding terminal carried by the bracket supporting the magneto generator and adapted to engage a rod carrying the fixed electrode. 25

In testimony whereof, I affix my signature. 30

ALBERT ERICKSON. 35
